No. 828,903.

PATENTED AUG. 21, 1906.

B. SHARP.
NON-REFILLABLE BOTTLE.
APPLICATION FILED OCT. 13, 1905.

UNITED STATES PATENT OFFICE.

BYRON SHARP, OF ST. LOUIS, MISSOURI.

NON-REFILLABLE BOTTLE.

No. 828,903.

Specification of Letters Patent.

Patented Aug. 21, 1906.

Application filed October 18, 1905. Serial No. 282,576.

To all whom it may concern:

Be it known that I, BYRON SHARP, a citizen of the United States, residing in the city of St. Louis and State of Missouri, have invented certain new and useful Improvements in Non-Refillable Bottles, of which the following is a specification:

This invention relates to the type of bottles known as "non-refillable" bottles.

10 In the accompanying drawings, forming part of this specification, in which like numbers of reference denote like parts wherever they occur, Figure 1 is a sectional view of the neck of a bottle, part of the devices for preventing refilling being shown in side elevation. Fig. 2 is a similar view, (the bottle being tilted downward,) said devices being shown in section. Fig. 3 is a detail showing a pair of grooves formed in the neck of the 15 bottle. Fig. 4 is a sectional view through the valve and connected parts. Fig. 5 is a top plan view of the same, parts being broken away. Fig. 6 is a top plan view of the protecting-cap for the valve, and Fig. 7 is a 20 sectional view of a modification thereof.

The wall of the neck of the bottle 1 contains annular grooves 2 and 3, the former serving to retain in position the valve, preventing the refilling of the bottle. The 25 groove 3 lies between the annular flange 4 and the neck-wall and is intended for the reception of a suitable packing 5, illustrated in the drawings as consisting of a rubber annulus. Same may be made, however, of aluminum or other suitable material. I prefer to 30 utilize a resilient material, for reasons which will hereinafter appear.

The valve 6 is hinged at 7 to a ring 8, formed of aluminium or other suitable non-40 corrosive material, to which are fastened, by screws 9 or other suitable means, a pair of leaf-springs 10, the unattached portions of said springs projecting in opposite directions relative to each other. A coiled spring 11, 45 coöoperating with the hinge 7, normally closes valve 6, being of sufficient strength for that purpose, yet being also sufficiently yielding to allow valve 6 to open under the pressure of the liquid in the bottle when same is tilted to 50 the position shown in Fig. 2. The lower side of the valve 6 is provided with an annular flange 12, which fits into an annular groove 13, formed in the upper surface of the ring 8, the whole of the valve 6 fitting into a countersink 14 in the upper surface of the ring 8, 55 so as to lie flush therewith, and thus present

no projection toward the exterior of the bottle. A peripheral groove 15 in the ring 8 receives the leaf-springs 10 at their point of attachment to said ring and is adapted to receive even the protruding portions of said springs when the ring 8 and connected parts are first introduced into the narrow part of the neck of the bottle. The opening in the neck of the bottle is narrowest at its mouth, 60 but gradually increases in diameter until it reaches its maximum at a point 16 approximately adjacent the lower end of the cork 17, at which point an angle is formed in the interior of the neck of the bottle, the diameter of 65 the opening therethrough gradually decreasing from that point downward until it is narrowest immediately above the groove 2. While passing through said narrow portion, as well as when passing through the mouth of 70 the neck of the bottle, the springs 10 will seat in the groove 15.

Fixed to the ring 8 and superimposed thereabove is a hemispherical cap comprising a stationary member 18 and a movable member 19, pivoted at 20 to the fixed member 18. The pivoted member 19 is either made heavy 80 enough or otherwise suitably weighted, as by the shoulder 21, to swing of its own weight toward the stop 22 when the bottle is turned 85 upside down or tilted into the position shown in Fig. 2. In Fig. 7 is illustrated a modification in which a shoulder or ridge formed in the member 18 is substituted for the pin 22. (Shown in Fig. 1.) It will also be observed 90 that the weighted shoulder 21 can be utilized as a stop by so arranging it as to strike the nearest edge 23 of the member 18. When the bottle is returned to its normal position, the member 19 falls from the position shown in 95 Fig. 2 to that illustrated in Fig. 1.

The cap formed of the members 18 and 19 constitutes a protection for the valve 6 to prevent its being held open from the outside of the bottle; but the valve itself constitutes the 100 means for preventing reentrance into the bottle of any liquid. As an additional precaution, and so as to prevent the insertion of a wire, for instance, to hold up the member 19 and to catch the valve 6 open while the bottle is 105 in the position shown in Fig. 2, a guard-disk 24 is provided in the neck of the bottle at a point above the member 18. Said guard-disk 24 may either be formed of reticulated material or, as shown in the drawings, it 110 may take the form of a pair of diaphragms having a plurality of openings therethrough,

- the openings 25 in the upper diaphragm being arranged in staggered relation to those in the lower diaphragm. The disk 24 is provided with the pair of springs 26, attached to it and operating like the springs 10, hereinabove described, and fitting into the groove 27, the springs 26 and groove 27 being preferably narrower vertically than the vertical width of springs 10 and groove 2.
10. The operation of the device is as follows: The bottle having been filled, annulus 5 is slipped down the neck of the bottle and into place in the groove 3, or it may be attached to the ring 8 and carried to its said position, 15 when the ring 8 and connected parts are introduced into the neck of the bottle. When the packing 5 consists of resilient material, it is made slightly higher than groove 3, and when the ring 8 is pressed down thereupon 20 said packing 5 is expanded laterally, so as more completely to fill the groove in which it is placed, and thus to render the device more water-tight. Moreover, the close pressure of the ring 8 upon the packing 5 from the top 25 renders said connection water-tight and also tends to push the ring 8 upward and to cause the springs 10 to bite upon the upper wall of the groove 2. The protrusion of the springs 10 into the groove 2 prevents the retraction 30 of the ring 8 from the neck of the bottle after it has been pushed into place and the springs 10 have sprung into the groove 2, and the bite of the springs 10 on the upper wall of the groove 2 and the upward pressure of the 35 packing 5 render the device stationary. When it is desired to pour out some of the contained liquid from the bottle, it is tilted into the position shown in Fig. 2, whereupon the pivoted member 19 swings out of the 40 way of its own weight, and the liquid causes the valve 6 to open against the mild pressure of spring 11. As soon as the bottle is returned to its normal vertical position the pressure of the liquid against the valve 6 is 45 relieved, and the spring 11 positively closes the valve, while the member 19 returns to the position shown in Fig. 1 by gravity.
- Having thus described my said invention, what I claim, and desire to secure by Letters 50 Patent, is—
1. In a device of the character described, the combination of the neck-wall of the bottle having formed therein a pair of annular grooves, a valve, a valve-seat, a packing located in one of said grooves and adapted to hold the valve-seat in place, and means connected with said valve-seat to enter the other of said grooves and to prevent retraction of same from the mouth of the bottle.
60. 2. In a device of the character described, the combination of the neck-wall of the bottle having formed therein a pair of annular grooves, a valve, a valve-seat, a packing located in one of said grooves, and means connected with said valve-seat to enter the other

of said grooves and to prevent retraction of same from the mouth of the bottle, said packing being so placed in one groove as to force said means to bite the upper wall of the groove containing same. 70

3. In a device of the character described, the combination of the neck-wall of the bottle having formed therein a pair of annular grooves, a valve, a valve-seat, a packing located in one of said grooves, and means connected with said valve-seat to enter the other of said grooves and to prevent retraction of same from the mouth of the bottle, said packing being slightly higher than the groove provided therefor, so that it is adapted to be 80 expanded by pressure of the valve-seat when the latter is forced into place.

4. In a device of the character described, the combination of the neck-wall of the bottle having formed therein a pair of annular grooves, a valve, a valve-seat, a packing located in one of said grooves, and means connected with said valve-seat to enter the other of said grooves and to prevent retraction of same from the mouth of the bottle, said 90 packing being slightly higher than the groove provided therefor, so that it is adapted to be expanded by pressure of the valve-seat when the latter is forced into place, and to tighten the hold of the means for preventing the retraction of said valve-seat.

5. In a device of the character described, the combination of a valve, a valve-seat, neck-wall of a bottle having a pair of annular grooves formed therein approximately at 100 right angles to each other, means connected with said valve-seat for entering one of said grooves and retaining said valve-seat from retraction, and resilient packing within the other of said grooves expansible under pressure of said valve-seat when said valve-seat is forced into place, and adapted to tighten the retention of said valve-seat in the neck of the bottle. 105

6. In a device of the character described, the combination of a valve-seat having a valve-controlled opening therethrough and a plurality of protecting devices, one of which is mounted on the valve-seat. 110

7. In a device of the character described, the combination with the neck-wall of the bottle of a valve, a valve-seat having a valve-controlled opening therethrough and a protecting-cap, comprising a pair of members, one stationary, and the other movable. 115 120

8. In a device of the character described, the combination with the neck-wall of the bottle of a valve, a valve-seat having a valve-controlled opening therethrough and a protecting-cap, comprising a pair of members, one stationary, and the other movable, said stationary member being fixed to the valve-seat. 125

9. In a device of the character described, the combination with the neck-wall of the 130

bottle of a valve, a valve-seat having a valve-controlled opening therethrough and a protecting-cap, comprising a pair of members, one stationary, and the other movable, said 5 stationary member being fixed to the valve-seat, and said movable member being pivoted to said stationary member.

10. In a device of the character described, the combination with the neck-wall of the 10 bottle of a valve, a valve-seat having a valve-controlled opening therethrough and a protecting-cap, comprising a pair of members, one stationary, and the other movable, said movable member being suitably weighted to 15 cause its actuation by gravity.

11. In a device of the character described, the combination with the neck-wall of the bottle of a valve, a valve-seat having a valve-controlled opening therethrough and a protecting-cap, comprising a pair of members, one stationary, and the other movable, said movable member being automatically actuatable in either direction by the movement of the bottle. 20

25. 12. In a device of the character described, the combination with the neck-wall of the bottle of a valve, a valve-seat having a valve-controlled opening therethrough and a protecting-cap, comprising a pair of members, one stationary, and the other movable, said stationary member being provided with means to limit the movement of said movable member. 30

13. In a device of the character described, 35 the combination with the neck-wall of the bottle of a valve, a valve-seat having a valve-controlled opening therethrough and a protecting-cap, comprising a pair of members,

one stationary, and the other movable, said members being provided with coacting means 40 to limit the movement of said movable member.

14. In a device of the character described, the combination with the neck-wall of the bottle of a valve-seat adapted to be fastened 45 therein, a spring-pressed flap-valve normally closing the opening into the body of the bottle, but actuatable by the weight of the liquid to open against the pressure of said spring, and a cap protecting the valve, said cap comprising one stationary and one movable member. 50

15. In a device of the character described, the combination with the neck-wall of the bottle having an annular groove therein of a ring or disk having a valve-controlled opening therethrough and a peripheral groove, 55 springs partly recessed in said peripheral groove and adapted to be received completely therein when subjected to pressure, but adapted normally to protrude partly 60 therefrom and into said annular groove.

16. In a device of the character described, the combination with the neck-wall of the bottle of a valve, a valve-seat having a valve-controlled opening therethrough and a protecting-cap, comprising a pair of members, one stationary and the other movable, said members being provided with suitable stops to limit the movement of said movable member. 65

In testimony whereof I have affixed my signature in presence of two witnesses.
